CAN OPENING DEVICE

Adam J. Dzialdowski, Berwick, Pa.

Application April 17, 1953, Serial No. 349,359

5 Claims. (Cl. 220—52)

1

The present invention relates to an improved opening device and more particularly to an opening device including guide means for use with cans having tear-strip openers.

Considerable difficulty is often encountered in opening cans carrying tear-strip openers circumferentially extending around the cans. This difficulty arises from the fact the tear-strips often are wound loosely and unevenly on the key during the unwinding of the strip. When this occurs, the strip usually becomes torn or broken thus preventing the can from being opened in the desired and proper manner. When this occurs, the housewife may try to remove the remainder of the strip by hand or by tools and oftentimes when doing this cuts or otherwise injures herself.

To eliminate this material disadvantage to tear-strip cans, there have been a wide variety of devices contemplated heretofore to aid in the removal of the tear-strip in the desired manner. However, these prior devices, although attempting to guide the tear-strip and ostensibly eliminate any loose winding, such devices have not positively insured a smooth, uniform and tight unwinding of the strip on the key with no possibility of slippage occurring during the unwinding. For example, one such device has provided a channel guide having spaced slotted openings in which the key is placed. When employing such prior device it is necessary that the key be held in the slot by pressure of the fingers against the key in the slots in order to prevent any slipping or accidental displacement of the key during the opening of a can. This prior device is undesirable since it requires the use of both hands to effect the unwinding. Moreover, it does not positively insure that the tear-strip will be wound uniformly and tightly without slippage and thus eliminate the possible tearing of the strip prior to the can being opened.

It is therefore a principal object of the present invention to provide a guide means for use with a conventional can key which will positively insure in the opening of a can by means of a tear-strip that the strip will be wound in a tight and uniform manner.

An additional object of the present invention is to provide a guide means for use in association with the conventional can key which will positively insure the retention of the key within the guide means at all times.

A further object of the present invention is to provide a guide means for use with a key which will require the use of only one hand in the operation of the device to remove the tear-strip from the can.

2

Still another object of the present invention is the construction of an improved key for association with one particular form of the guide means of the present invention.

5 A still further object of the present invention is the construction of a guide device for use in association with a key which may be detachably secured to a conventional can in a manner similar to that now employed for carrying the key.

10 Other and additional objects will become apparent from the following description taken in conjunction with the accompanying drawing.

Broadly stated, the present invention is a tear-strip guide comprising a base section having its center portion cut out, the opposite sides of the cut-out portion immediately adjacent thereto being bent upwardly and downwardly respectively to form spaced tongue portions, a pair of spaced side members united to the bottom member along each side thereof and extending upwardly therefrom at right angles thereto, a pair of aligned openings in each of said side members with at least one opening being completely enclosed, said openings being centrally positioned and in transverse relationship to the central cut-out area of said bottom member. In the modified form of the device the side members will be provided aligned holes and a key having a slot running lengthwise of the shaft of the key from the bottom upwardly.

30 To the accomplishment of the foregoing and related ends, the present invention then consists of the means hereinafter fully described and particularly pointed out in the claims, the annexed drawing and the following description setting forth in detail certain means in the carrying out of the invention, such disclosed means illustrating, however, but one of various ways in which the principle of the invention may be employed.

40 The present invention is illustrated, by way of example, in the accompanying drawing in which:

Fig. 1 is a perspective view of a guide means made in accordance with the present invention illustrating how it is secured to the top cover 45 of the can along side the key;

Fig. 2 is a perspective view of the guide means made in accordance with the present device illustrating how it is secured to the can along the detachable tear-strip;

Fig. 3 is a top plan view of a guide device made in accordance with the present invention;

Fig. 4 is a cross-section taken on line 4—4 of Fig. 3;

Fig. 5 is an end view of the device shown in

55 Fig. 3 particularly illustrating the inclination of the tongue elements by which the tear-strip is evenly wound;

Fig. 6 is a side view of the device shown in Fig. 3 illustrating how the key is detachably engaged by one side of the guide device;

Fig. 7 is a top view of a device made in accordance with the present invention illustrating the position of the key and the guide means after a tear-strip is removed and wound from a can; and

Fig. 8 is a perspective view of a modified form of a key and guide device made in accordance with the present invention.

Referring now to the drawing and with particular reference to Figs. 3-6, the guide device made in accordance with the present invention and generally designated by reference numeral 10, comprises a bottom member 11 having a small central area cut out transverse to its longitudinal axis, spaced end sections 12 and 13 at each end thereof, a first tongue section 14 united at one end to the inside edge of said end section 12 and upwardly inclined therefrom, a second tongue section 15 secured to the opposite end section 13 along its inside edge and extending downwardly therefrom. The upwardly and downwardly inclined tongue sections 14 and 15 extend inwardly toward one another and toward the cut-out area. The tongue sections 14 and 15 are spaced from one another at their free edges and with the inclination of the tongue sections resulting in each lying substantially parallel to one another with their free ends extending in opposite directions. This construction results in an area in which the tear-strip will be wound with the free edges of the tongue section 14 and 15 functioning as resilient bearing points against the tear-strip during its unwinding at diametrically opposite points.

A pair of spaced side members 16 and 17, which may be of triangular configuration as shown, are joined at their respective bottom edges adjacent their ends to the end sections 12 and 13 at right angles thereto. This construction defines the guide channel in which the tear-strip will be wound. Side member 16 is provided with a circular opening 17 at a point above and centrally with respect to the cut-out section of the bottom member 11. The side member 16 having the circular hole 17 will function as the bottom of the guide device when in use. The spaced opposite side member 18 which will function as the top of the guide device when it is in use is provided with a slot 18a in which the neck portion is smaller in diameter than the main area of the slot in order to permit the shank of the key to be inserted therein by a snap action and yet be freely rotatable therein.

Therefore, in one form of the invention, there is provided a cooperating hole and a snap-action slot spaced from one another. In this form, the bottom member must always contain the hole and the top member contain the slot in order to prevent the accidental slipping of the key from the guide device while in use. If the key is confined in a hole at its bottom accidental displacement cannot occur. However, while this is the preferred form of the invention, two holes may be employed rather than a hole and a slot. This modified form will be discussed and described hereinafter.

In the operation of this form of the invention, the guide device 10 may be secured to the top surface of the can (see Fig. 1) or to the side of the can along the tear-strip (see Fig. 2) by means of spot soldering or the like. When the

guide device 10 is secured to the top surface it is removed therefrom in a manner similar to that employed in removing a conventional key therefrom. The guide device 10 is placed against the tear-strip 19 having a free starting end 20 which is tilted or bent upwardly into the cut-out area of the bottom member 11. The key 21 is then removed from the can and inserted in the opening 17 of the bottom or side member 16 and the free end of the tear-strip 20 is inserted in the slot 22 of key 21. The upper half of the key 21 is then snapped into the slot 18a of the opposite side member 18. The tear-strip is then removed by winding the tear-strip clockwise in a speedy and safe manner.

During the unwinding of the strip 19 the upwardly inclined section 14 and the downwardly inclined section 15 will engage the tear-strip during its unwinding at all times and will act as tensioning or bearing means as well as guide means for the tear-strip at opposite points thereof to insure a constant uniform pressure against the moving surface on either side thereof. As the tear-strip is unwound the inclined portions 14 and 15 are resilient enough to be expanded at the free ends as the size of the strip increases. It is particularly important that these inclined sections 14 and 15 engage the strip at opposite points and to function in cooperative relationship with the side members 15 and 16 in order to insure the necessary opposite pressure against the moving surface of the tear-strip 19 while the side members 15 and 16 act to prevent any lateral displacement of the winding strip during the opening of the can.

In employing the device when attached to the side of the can as shown in Fig. 2, the guide device 10 is associated on the tear-strip 19 over the free starting end 20 with the free end 20 being slightly turned upwardly in starting position. The guide device 10 is secured to the tear-strip by a very light spot solder or similar means. To remove the tear-strip 19, the key 22 is inserted at the hole 17 and the free end 20 inserted in the slot 22 and the upper half of the key 21 is then snapped into the restricted slot 18a and held in place thereby. The key 21 is then moved clockwise and with a slight pressure the guide device 10 is broken from the tear-strip and the winding therebetween is begun. This method of attaching is very desirable since the manufacturer of the can can positively insure the proper positioning of the guide on the tear-strip and permits the removal of the tear-strip solely by means of one hand.

In the modified form shown in Fig. 8, the guide device is of substantially identical construction as the guide device 10 with the exception that the side member or top section 18 is provided with a hole 23 rather than a slot as shown in Fig. 6. When this modified form of the device is employed a particular type key is desirable and necessary. This particular type key comprises a shank 24 and a top loop 25 secured at one end thereof. The shank 24 is split centrally and upwardly from the bottom free end forming spaced legs 26 and 27. When employing the modified form of the device shown in Fig. 8, the free end 28 of the tear-strip 19 is raised in starting position and the modified key is inserted in the top hole 23 in side member 18 and pushed downwardly with the spaced legs 26 and 27 passing between and on either side of the free end 28 of the tear-strip 19 and into hole 17 of the side member 16. The purpose of the modified key

is to permit the ready engagement of the free end of the tear-strip 20 during the insertion of the key in the aligned openings. If the key was not slotted considerable difficulty would be encountered in properly positioning the tear-strip in the slot of a conventional key.

In the preceding description, there has been no reference made as to the type of material that may be employed in the construction of the device. The device may be made of any suitable material possessing the desired or necessary rigidity and yet be light in weight. The preferred material to be employed is any suitable metal such as, for example, tin or aluminum, although the guide device may be made from other materials such as, for example, plastic, fibreboard, etc. Moreover, the material to be employed should be one in which the device can be made as a unitary one-piece article. For example, when employing metal, the guide device may be stamped from a metal blank and folded into the desired position.

While the foregoing illustrative embodiments of the guide device and modified key construction made in accordance with this invention are preferred, it is to be understood that the particular embodiments described hereinbefore are illustrative in character. For example, other and apparent modifications are possible without departing from the scope and spirit of the invention.

Having thus described the invention, I claim:

1. A guide device for use with cans having

tear-strip openers comprising a base member, oppositely inclined tongue portions connected to and extending from each end of said base toward one another, the free ends of said inclined tongues being spaced from each other forming an opening in the middle portion of said base member, a pair of side members joined on either side of said base member and extending upwardly therefrom at right angles thereto, a pair of aligned openings in said side members with at least one of said openings being a hole.

2. A guide device in accordance with claim 1 wherein the side members are provided with aligned holes.

3. A guide device in accordance with claim 1 wherein the side members are generally triangular in configuration.

4. A guide device in accordance with claim 1 wherein the material is metal and the component parts are integrally secured to one another.

5. A guide device in accordance with claim 1 wherein one side member is provided with a hole and the other side member is provided with a guide-way slot in alignment with said hole.
